CLAIM

The ornamental design for an insulated structural building panel with a thermal break attachment attached to the front of the panel, as shown and described.

DESCRIPTION

FIG. 1 is a perspective view showing my new design for an insulated structural building panel with a thermal break attachment attached to the front of the panel from the front, top, and left side;

FIG. 2 is a perspective view showing the design from the rear, top and left side;

FIG. 3 is a perspective view showing the design from the rear, top and right side;

FIG. 4 is a perspective view of the design showing the design from the top, rear and right side;

FIG. 5 is a perspective view showing the design from the bottom, rear and right side;

FIG. 6 is a left side elevational view thereof;

FIG. 7 is a right side elevational view thereof;

FIG. 8 is a front elevational view thereof;

FIG. 9 is a rear elevational view thereof;

FIG. 10 is a top plan view thereof; and,

FIG. 11 is a bottom plan view thereof.
